(57) **CLAIM**

The ornamental design for a visor with fur, as shown and described.

DESCRIPTION

FIG. 1 is a left side view in elevation of a visor with fur according to an embodiment of the present invention;

FIG. 2 is a right side view in elevation of the visor with fur shown in FIG. 1;

FIG. 3 is a front view in elevation of the visor with fur shown in FIG. 1;

FIG. 4 is a rear view in elevation of the visor with fur shown in FIG. 1;

FIG. 5 is a top view in plan of the visor with fur shown in FIG. 1; and,

FIG. 6 is a bottom view in plan of the visor with fur shown in FIG. 1.

The design consists partly of fur. Inconsistencies between the way the fur appears in the different views are understood to be caused by the variations in the organic material of the fur, and by the different viewpoints from which the visor with fur is shown. The minor variations from one view to another do not render the designs patentably distinct, but are due to the organic nature of the fur.

The evenly-spaced broken lines represent stitching. The long-and-two-short-segmented broken lines are for the purpose of illustrating environment matter and form no part of the claimed design.
